UNITED STATES PATENT OFFICE.

JUDSON D. PERRY, OF DETROIT, MICHIGAN.

DESIGN FOR A BADGE.

SPECIFICATION forming part of Design No. 21,095, dated October 6, 1891.

Application filed May 6, 1891. Serial No. 391,830. Term of patent 14 years.

To all whom it may concern:

Be it known that I, JUDSON D. PERRY, a citizen of the United States of America, residing in the city of Detroit, county of Wayne, 5 and State of Michigan, but stopping for a time at Omaha, in the county of Douglas and State of Nebraska, have invented and produced a new and original Design for Badges, Banners, and Pictures, especially intended for campaign uses, of which the following is a specification, reference being had to the accompanying prints, forming a part thereof.

The object of the invention is to form a badge representing the conflict between prohibition and alcohol, and which will appeal at the same time to the patriotism of the people by inferring that King Alcohol is not only the enemy of the peace and prosperity of the country, but also the enemy of the country 20 itself, which is represented in the design by a flag and a soldier.

My design consists of a representation on the left side of King Alcohol in regal attire, standing with one foot upon a barrel and holding in one hand a glass or goblet, while in the

other he grasps a sword, while behind him is the representation of a dragon and in the background a saloon. Upon the right is the figure of a soldier and the United States flag, the soldier pointing with one hand to the flag 30 while in the other he grasps a sword. Behind him are represented the factories and houses of a flourishing city. Above this picture I have an emblematical design which may represent the national coat of arms, showing 35 an eagle with spread wings upon a shield, and a number of flags in the background, with a surrounding scroll. Above the figure, on the scroll and beneath the picture, are spaces in which suitable inscriptions may be placed. 40

What I claim is—

The design for a badge, as herein described and shown.

In testimony whereof I have signed this specification in the presence of two witnesses. 45

JUDSON D. PERRY.
